UNITED STATES PATENT OFFICE.

JOHN GEORGE HOWARD, OF LONDON, ENGLAND.

OAR.

Application filed May 5, 1924. Serial No. 711,248.

To all whom it may concern:

Be it known that I, JOHN GEORGE HOWARD, of 56 Victor Road, Andover Road, Holloway, London, N. 7., a subject of the King of England, have invented new and useful Improvements in Oars, of which the following is a specification.

This invention relates to a form of oar for a rowing boat which may be operated readily by the oarsman when facing in the direction in which the boat is being rowed.

According to the present invention an oar comprises a blade portion and a handle portion which are connected so that when the handle is moved forward the blade also moves forward and when the handle is moved backward the blade moves backward.

Conveniently the blade and the handle take the form of two interconnected levers 20 pivotally supported by a carrier so as to project therefrom in opposite directions.

In one construction the interconnecting means take the form of two toothed segments engaging with one another, one rotated by the handle and the other moving the blade.

Preferably the carrier is provided with means to support it from the boat which prevent rotation in the plane of movement 30 of the blade or handle but permit it to be swung up or down on an axis transverse to the general direction of the oar to impart rising and dipping movement to the oar. In this way the reaction at the rowlock, which 35 differs from that of an ordinary oar in that it is mainly a torque between the carrier and the boat, is satisfactorily met by the same means which provide for the rising and falling of the oar.

It is desirable that "feathering" should be provided for, but owing to the relative movement of the blade and handle portions, they are not in line with one another except momentarily at a particular position of the oar. To accomplish the end in view the blade and handle may be mounted to rotate about their own axes in cradles pivoted to the carrier, and the blade and handle may be interconnected by gearing such that 45 feathering movements imparted to the handle are copied by the blade. The sense of the movement should be reversed owing to the reversal of the direction of swing of the blade.

The accompanying drawings illustrate by

way of example constructions according to the invention.

Fig. 1 is a side elevation, half in section of one construction of oar, the ends of the handle and blade being broken away; 60

Fig. 2 is a plan of the same partly broken away to show the gearing;

Fig. 3 is a side elevation of another construction;

Fig. 4 is a vertical section through a third 65 construction;

Fig. 5 is a detail side elevation of the frame shown in Fig. 4; and

Fig. 6 is a plan of the underside of the 70 same.

Figs. 7 and 8 are plan and elevation of an alternative construction.

Like reference characters indicate like parts in all the figures.

Referring to Figs. 1 and 2, the oar comprises a handle portion A in the form of a light metal shaft having a suitable grip at its free end (not shown), and a blade portion B the outer end of which is flattened and shaped like an ordinary oar. The handle A is supported in a cradle C and the blade B in a similar cradle C', and the cradles are pivoted at C² and C³ respectively on a carrier D. The cradles C and C' are light metal frames having cross members C⁴ which carry the pivot pins C², C³ and side members which extend from the ends of the cross members on each side of the shafts A and B and converge on bearings C⁵ for the shafts. The cradles also 80 have toothed segmental portions C⁶, C⁷ at their adjacent ends which intermesh. The handle portion A extends through the cross member C⁴ of the cradle C and carries a mitre wheel E located in the space between the segment C⁶ and the cross member C⁴. The mitre wheel E meshes with a second mitre wheel E' concentric with the pivot pin C². A spur wheel E² of the same radius as the segment C⁶ is journalled freely 85 upon the pivot pin C² and carries the mitre wheel E'. Thus any rotation of the handle portion A in its cradle will be transmitted by the mitre wheels E and E' to the spur wheel E². The wheel E² will also rock to 90 and fro with the movements of the cradle C, the two movements being superimposed.

The blade portion B also extends through the cross members C⁴ of its cradle C', and carries a mitre wheel E³, but this wheel is 105 110

located in the side of the cross member C^4 which is remote from the segment C^7 of the cradle. The mitre wheel E^3 meshes with a mitre wheel E^4 carried upon a spur wheel E^5 of the same radius as the segment C^7 . The wheel E^4 is journalled to turn freely upon the pin C^3 like the wheel E^2 upon the pin C^2 . The spur wheels E^5 and E^2 mesh together and thus any rotation of the handle portion A is reproduced by a corresponding rotation of the blade portion B. Owing however to the wheel E^3 being on the opposite side of the cross member C^4 from the segment C^7 , whereas the wheel E is in the same side of its cross member C^4 as the segment C^6 , the rotation of the blade is reversed compared with that of the handle.

The carrier D is arranged to enclose the mechanism described to protect it. The carrier consists of two elliptical plates D^2 , D^3 , parallel to one another with the gearing between them. The two pins C^2 , C^3 are given their bearing in the plates, and as will be seen all the mechanism is carried on these pins, which are best, as shown, formed in one piece with the cradles. Each of the plates D^2 , D^3 , has an arm D^4 projecting inwardly at right angles from it on one side, and a pair of such arms D^5 on the other side. The arm D^4 one plate is received between the arms D^5 of the other and locked in place. The arms D^4 each carry a pivot pin D^6 . The two pivot pins D^6 are in line with one another and their axis is transverse to the general direction of the oar but lies in or parallel to the plane of their movements. The pivot pins D^6 permit rising and falling movements of the oar. When the oar is in use they are suitably supported by a bracket or rowlock designed to fit them, which is fixed on to the side of the boat.

The construction illustrated in Fig. 3 is identical with that just described with the exception that the segments C^6 , C^7 are omitted. In this case not only the feathering motion but also the swinging motion is transmitted from the handle to the blade by the spur wheels E^2 , E^3 . To do this the oarsman must hold the handle from rotation during the swing by his own muscular force.

Fig. 4 shows a construction identical with that of Figs. 1 and 2 as to its main working parts. The carrier D, however, is in this case formed in a single piece as shown in detail in Figs. 5 and 6. To permit of assembly of the mechanism within the carrier there are removable bushes F to receive the pins C^2 , C^3 . The distance sleeves G which surround the lower part of the pins C^2 , C^3 below the cradles C , C' are split, and either hinged along the back or springy. If hinged they must be provided with some form of fastening, not shown.

To assemble this construction, the cradle units are first put together with the spur

wheels E^2 or E^5 and their corresponding mitre wheels. The bush F is slipped on the pivot. The cradle unit is then inserted as shown in Fig. 4, the bush F being loose on the pivot. The parts are so proportioned that the pin C^2 (for example) can be entered in the hole for the bush F while the pin is on the slant as in the drawing, can be brought under the hole for it in the upper plate D^2 next, and can then be passed up through that plate far enough for the lower end of the pin to be well above the inside of the plate D^3 . The bush is then put in place, the spur wheel E^2 and mitre wheel E^3 are positioned below the end of the pin C^2 , and the pin is passed down through them into the bush. It only remains to put the split distance sleeve G in place.

In order to increase the clearance for assembling, the plate D^2 may be hollowed out over the mitre wheel E or E^3 as shown in dotted lines at H in Fig. 5.

The construction shown in Figs. 7 and 8 is adopted to avoid making a special construction for the holes for the pivots. It has the further advantage of being extremely rigid. The pieces L^1 , L^2 and L^3 are made preferably in one, the clearance between L^1 and L^3 being slightly less than that shown between the corresponding parts in Figs. 1 and 2. The piece L^3 has two slots L^4 at opposite ends and on either side of the slots is a tapped screw hole P^2 .

With this construction the vertical members are inserted in their pivot holes at one end and have the pivot pins projecting at the other end through the slots L^4 . The parts being thus assembled, an outer plate O with two pivot holes O' and four screw holes P is placed in position, the positioning of the holes O' and P being carefully chosen in relation to one another. With this construction, this device has all the advantage of a unit construction.

Having now particularly described and ascertained the nature of my said invention and in what manner the same is to be performed, I declare that what I claim is:

1. In an oar the combination of a handle-portion, a blade-portion, cradles in which the handle and blade portions are carried and rotatably mounted so as to turn about their own axes, a carrier upon which the cradles are pivoted so that handle and blade can swing forwardly and rearwardly, means interconnecting the cradles so that when the handle is swung forward the blade is swung forwardly also, a toothed gear mounted coaxially with the pivot of each cradle to rotate relatively thereto, said gears being operatively connected together, and further toothed gears connecting each said gear with the handle and blade respectively, substantially as and for the purpose set forth.

2. In an oar the combination of a handle-portion, a blade-portion, cradles in which the handle and blade portions are carried and rotatably mounted so as to turn about their own axes, a carrier upon which the cradles are pivoted so that handle and blade can swing forwardly and rearwardly, means interconnecting the cradles so that when the handle is swung forward the blade is swung forwardly also, a toothed gear mounted coaxially with the pivot of each cradle to rotate relatively thereto, said gears being operatively connected together, toothed bevel wheels upon each said gear and toothed bevel wheels which mesh with the first said bevel wheels upon the handle and blade, substantially as and for the purpose set forth. 50
- 5 10 15 20 25 30 35
3. In an oar the combination of a handle portion, a blade-portion, a carrier, cradles in the form of cross-members pivoted upon the carrier with stays extending from the ends thereof to outer bearings, the handle and blade portions being rotatably supported in the cradles so as to turn about their own axes in the cross-members and the outer bearings, means interconnecting the cradles so that when the handle is swung forward the blade is swung forwardly also, a toothed gear mounted coaxially with the pivot of each cradle to rotate relatively thereto, said gears being operatively connected together, toothed bevel wheels upon each said gear and toothed bevel wheels which mesh with the first said bevel wheels upon the handle and blade, substantially as and for the purpose set forth. 65
- 20 25 30 35
4. In an oar the combination of a handle-portion, blade-portion, a carrier, cradles in the form of cross-members pivoted upon the carrier with stays extending from the ends thereof to outer bearings, the handle and blade portions being rotatably supported in the cradles so as to turn about their own axes in the cross-members and the outer bearings, arc-shaped gear-segments supported by the cross-members of the cradles and in mesh with one another so that when the handle is swung forward the blade is swung forwardly also, a toothed gear mounted co- 70 75 80 85 90
- 40 45
- axially with the pivot of each cradle to rotate relatively thereto, said gears being operatively connected together, and further toothed gears connecting each said gear with the handle and blade respectively, substantially as and for the purpose set forth. 55
- 5 10 15 20 25 30 35
5. In an oar the combination of a handle-portion, a blade-portion, a carrier, cradles in the form of cross-members pivoted upon the carrier with stays extending from the ends thereof to outer bearings, the handle and blade portions being rotatably supported in the cradles so as to turn about their own axes in the cross-members and the outer bearings, means interconnecting the cradles so that when the handle is swung forward the blade is swung forwardly also, a toothed gear mounted coaxially with the pivot of each cradle to rotate relatively thereto, said gears being operatively connected together, toothed bevel wheels upon each said gear and toothed bevel wheels which mesh with the first said bevel wheels upon the handle and blade, substantially as and for the purpose set forth. 70
- 20 25 30 35
6. In an oar the combination of a handle-portion, a blade-portion, a carrier, cradles in the form of cross-members pivoted upon the carrier with stays extending from the ends thereof to outer bearings, the handle and blade portions being rotatably supported in the cradles so as to turn about their own axes in the cross-members and the outer bearings, arc-shaped gear-segments supported by the cross-members of the cradles and in mesh with one another so that when the handle is swung forward the blade is swung forwardly also, a toothed gear mounted coaxially with the pivot of each cradle to rotate relatively thereto, said gears being operatively connected together, toothed bevel wheels upon each said gear and toothed bevel wheels which mesh with the first said bevel wheels upon the handle and blade, substantially as and for the purpose set forth. 85
- 20 25 30 35

In testimony whereof I affix my signature.

JOHN GEORGE HOWARD.
